Chang

[11] Patent Number: Des. 414,742

[45] Date of Patent: ** Oct. 5, 1999

[54] BATTERY RECHARGER

[76] Inventor: **Yi-Huang Chang**, No. 5, 178 Lane,
Sec. 1, Ping-Tung Rd., Ping Chen City,
Taoyuan, Taiwan, 324

[**] Term: **14 Years**

[21] Appl. No.: **29/076,434**

[22] Filed: **Sep. 9, 1997**

[51] LOC (6) Cl. **13-02**

[52] U.S. Cl. **D13/107; D13/108**

[58] Field of Search D13/107, 108,
D13/118; D14/149, 251, 253; 320/110-115
